UNITED STATES PATENT OFFICE.

EDWARD JAMES TRIMBEY, OF WINDSOR, QUEBEC, CANADA.

STUFF-METER.

1,161,168.

Specification of Letters Patent. Patented Nov. 23, 1915.

Application filed December 5, 1914. Serial No. 875,720.

To all whom it may concern:

Be it known that I, EDWARD JAMES TRIMBEY, a citizen of the United States, residing at Windsor, in the county of Rich-
mond, in the Province of Quebec, Dominion
5 of Canada, have invented a new and useful Apparatus, Known as a Stuff-Meter, for Determining and Regulating the Per Cent. Consistency of Wet Paper-Stock or of Wet
10 Pulp, of which the following is a specifica-
tion.

In the present state of the art of paper making there is no rapid method of determining the per cent. consistency of wet pulp
15 as it is pumped to the beaters or to the mixing tanks, or of wet paper stock as it is pumped to the head-box of the Jordan engine or as it is pumped to the head-box of the paper machine, the Jordan engine being a machine
20 for further refining the fibers after having passed through the beaters and before going to the paper machine.

The term "per cent. consistency" as used in this specification means the number of
25 parts of bone-dry matter in one hundred parts of wet pulp or of wet paper stock.

The object of my invention is to afford a convenient and rapid method of ascertaining, by inspection, the per cent. consistency of wet pulp or of wet paper stock containing from three parts to five parts of bone-dry matter per one hundred parts of wet pulp or of wet paper stock as the same is being pumped for use in the manufacture of
35 paper, or, for indicating the amount of water which must be added to a given mass of such wet pulp or of such wet paper stock to dilute same to a predetermined lower per cent. consistency, for the purpose of more
40 closely regulating the proportions of the various kinds of pulp used, and, by maintaining a more nearly uniform per cent. consistency of the wet paper stock supplied to the paper machine to facilitate the obtain-
45 ing of an approximately uniform weight per ream of the paper made.

To accomplish my object I employ two chambers, one, to which a portion of the wet pulp or the wet paper stock the per
50 cent. consistency of which is to be determined, is conducted, is provided with an overflow dam for maintaining a constant level and therefore a constant head on an unalterable orifice cut in a plate of thin
55 metal which is placed in the bottom of this chamber and the discharge from which

passes into the other chamber; this second chamber communicates at the bottom with an approximately horizontal unalterable spout of suitable length and cross-sectional 60 area. The rate of flow into this second chamber is a definite amount being controlled by the constant head in the first chamber and the size of the unalterable discharge orifice from same. The head in the 65 second chamber is largely controlled by the frictional resistance opposing the flow of the wet pulp or the wet paper stock in the unalterable spout communicating therewith, and as this frictional resistance varies with 70 the per cent. consistency of the wet pulp or of the wet paper stock, either the per cent. consistency or the amount of water to be added for the desired dilution, is indicated by the height to which the level of the wet pulp or wet paper stock rises in this chamber. The height is shown by means of a float supported upon the surface of the wet pulp or wet paper stock; this float carries a pointer moving in front of a scale whose 75 graduations are determined by actual tests, for the grade of wet pulp or of wet paper stock passing through the stuff meter. That the float may not become spattered or covered by the incoming wet pulp or wet paper stock it is protected by means of an adjustable baffle, which is so adjusted that it will project but a short distance beneath the surface, so as to guard against the formation of a stratum of a high per cent. consistency 80 which would gradually be formed if the baffle projected for any considerable distance beneath the surface and which would bind against the sides of the chamber and interfere with the free movement of the surface level of the wet pulp or wet paper stock and thus with the movement of the float.

When using this apparatus the aim would be to have the wet pulp or the wet paper stock in the supply chests at a somewhat higher per cent. consistency than it is desired to maintain at the head-box of the paper machine or in the wet pulp pumped to the beaters or to the mixing tanks and thus allow for the addition of a variable amount of water for thinning, for while the wet pulp or the wet paper stock can be easily diluted if of too high a per cent. consistency, it cannot be readily thickened if too dilute.

The essential arrangement of my invention is that a float, to which is attached a

pointer so guided as to pass in front of a graduated scale, should show the depth or head of wet pulp or of wet paper stock in a chamber communicating at the bottom with 5 an approximately horizontal unalterable spout when the rate of flow into this chamber and through this spout is the amount determined by the discharge through an unalterable orifice in a plate of thin metal under the influence of a constant pressure, this constant pressure being maintained by means of an overflow dam of a given height 10 in a separate chamber in the bottom of which is located the unalterable orifice. It 15 is also essential that the chamber communicating at the bottom with the unalterable spout should be provided with a baffle which can be vertically adjusted, that the plane of this baffle should be approximately perpendicular to the axis of the spout, and that the 20 wet pulp or the wet paper stock should enter the chamber at the top and on the side of the baffle opposite to that at which communication is had with the spout.

25 As it is the general practice to use a head-box in which a constant level is maintained for regulating the supply to the Jordan engines or to the paper machines the unalterable orifice can be located in the bottom of 30 the regular head-box in such cases. The unalterable spout is preferably provided with a contracted outlet end to resemble a nozzle, though this feature is not essential; this 35 spout may either be straight, as shown in the accompanying drawings, or be bent if found more convenient.

One construction of my apparatus is shown by the accompanying drawings in which—

40 Figure 1 is a sectional elevation on the line A—A of Fig. 2; Fig. 2 is a top view; and Fig. 3 is a diagrammatic view showing the flow connections.

45 Similar numbers refer to similar parts in both views.

A portion of the wet pulp or of the wet paper stock, the per cent. consistency of 50 which is to be determined, enters the chamber 1 through the pipe 2 and flows into one compartment 10 of the chamber 5 through the unalterable orifice 3 in the thin plate of metal 4; the excess not passing through the orifice 3 flows over the partition or dam 6 and passes back to the supply chest 7 through the pipe 7. The upper part of the chamber 5 is divided into two compartments 10 and 11 by the movable partition 8 which is adjustable vertically and is restrained 55 from sidewise movement by the grooves 9. In the compartment 11, protected from the spattering, and the agitation of the surface caused by the incoming wet pulp or wet paper stock, by the movable partition 8 is the float 12 to which is attached the stem 13 60 carrying the pointer 14 which passes in front

of the graduated scales 15 as the surface level changes and the float 12 rises and falls in response thereto. The stem 13 is guided and restrained from sidewise movement by the guides 16 which are attached to the body 70 of the chamber 5, and which also support the graduated scales 15. After passing through the chamber 5 the wet pulp or the wet paper stock passes through the unalterable spout 17 and is discharged through the 75 contracted end 18 of this spout and is conducted back to the supply chest by the pipe 20, having a suitable inlet 19 and discharging into the pipe 21, into which the pipe 7 also discharges. From the supply chest 22, 80 the pulp or paper stock is circulated through the main supply pipe 23 by means of the pump 24, a portion of the pulp or paper stock being discharged through the branch pipe 2 into the chamber 1. The regulable 85 water supply pipe is indicated at 25.

I do not wish to restrict myself to this specific construction of the stuff meter, but what I claim as my invention is,—

1. A stuff meter for wet pulp and wet paper stock, comprising a constant level chamber having a discharge orifice maintained under a constant head of the pulp or paper stock, a variable level chamber arranged to receive the pulp or paper stock discharged from said orifice and provided with an outlet of suitable size and proportion to cause a frictional resistance to the flow of the pulp or paper stock therethrough, and thereby maintain a head of the pulp or paper stock within the chamber varying with its consistency and frictional resistance, and means for indicating variations in the head of the pulp or paper stock in said chamber; substantially as described. 105

2. A stuff meter for wet pulp and wet paper stock, comprising a constant level chamber having an overflow dam for maintaining a constant level therein and provided in its bottom with a discharge orifice 110 in a thin plate of metal, and a variable level chamber arranged to receive the pulp or paper stock discharged under a constant head through said orifice; substantially as described. 115

3. A stuff meter for wet pulp and wet paper stock, comprising a constant level chamber having a discharge orifice maintained under a constant head of the pulp or paper stock, a variable level chamber arranged to receive the pulp or paper stock discharged from said orifice and provided with an outlet of suitable size and proportion to cause a frictional resistance to the flow of the pulp or paper stock therethrough, and thereby maintain a head of the pulp or paper stock within the chamber varying with its consistency and frictional resistance, said variable level chamber having an 120 adjustable partition therein dividing the 125 130

- same into two compartments, in one of which the pulp or paper stock is received, a float within the other of said compartments arranged to be actuated by variations in the 5 level of the pulp or paper stock, and a pointer carried by said float and coöoperating with a suitable scale for indicating the consistency of the pulp or paper stock; substantially as described.
- 10 4. A stuff meter for wet pulp and wet paper stock, comprising a constant level chamber having a discharge orifice maintained under a constant head of the pulp or paper stock, a variable level chamber arranged to receive the pulp or paper stock 15 discharged from said orifice and provided with an outlet of suitable size and proportion to cause a frictional resistance to the flow of the pulp or paper stock there- 20 through, and thereby maintain a head of the pulp or paper stock within the chamber varying with its consistency and frictional resistance, said variable level chamber having an adjustable partition therein divid- 25 ing the same into two compartments, in one of which the pulp or paper stock is received, a float within the other of said compartments arranged to be actuated by variations in the level of the pulp or paper stock, and 30 a pointer carried by said float and coöperating with a suitable scale for indicating the amount of water to be added to a given mass of the pulp or paper stock to dilute the same to a predetermined lower consistency; sub- 35 stantially as described.
5. A stuff meter for wet pulp and wet paper stock, comprising a constant level chamber having a discharge orifice maintained under a constant head of the pulp or paper stock, 40 a variable level chamber arranged to receive the pulp or paper stock discharged from said orifice and provided with an outlet discharge pipe leading from the bottom
- thereof at one side, said discharge pipe being of suitable size and proportion to cause 45 a frictional resistance to the flow of the pulp or paper stock therethrough, and thereby maintain a head of the pulp or paper stock within the chamber varying with its consistency and frictional resistance, said 50 variable level chamber having an adjustable partition therein dividing the same into two compartments, from one of which the discharge pipe leads and into the other of which the pulp or paper stock is received, and a 55 float in the former of said compartments, arranged to be protected from spattering of the inflowing pulp or paper stock by said partition; substantially as described.
6. A stuff meter for wet pulp and wet 60 paper stock, comprising a constant level chamber having a discharge orifice maintained under a constant head of the pulp or paper stock, a variable level chamber arranged to receive, at one side thereof, pulp 65 or paper stock discharged from said orifice, and provided with an outlet discharge pipe from the bottom thereof at the other side of suitable size and proportion to cause a frictional resistance to the flow of the pulp 70 or paper stock therethrough, and thereby maintain a head of the pulp or paper stock within the chamber varying with its consistency and frictional resistance, an adjustable partition in said chamber below which 75 the pulp or paper stock must pass, and a float on the opposite side of said partition from the pulp or paper stock inlet, whereby the pulp or paper stock in said variable level chamber is kept in motion and continually changing; substantially as de- 80 scribed.
